FREDERICK M. FURBER, OF REVERE, MASSACHUSETTS.

TEMPERATURE-CONTROLLING APPARATUS FOR INTERNAL-COMBUSTION ENGINES.

Application filed May 27, 1916. Serial No. 100,411.

The invention relates to the automatic controlling of temperature in internal combustion engines and has particular reference to that type in which the temperature is controlled by the regulation of the air which cools the radiator. Heretofore apparatus of this type has been constructed in which the volume of air passing through the radiator is regulated by the opening and closing of shutters which restrict the flow. These shutters, in turn, are automatically operated by a thermal motor, which is arranged to be under the influence of the heat from the engine. Inasmuch, however, as the limits within which it is desirable to maintain the temperature are comparatively close to each other, it is difficult to obtain an effective thermal motor which will be operated by such slight temperature changes. I have therefore devised a construction in which the shutters or other mechanism are operated by motive power other than that derived from temperature variations, but which is nevertheless controlled thereby.

Any suitable motor may be employed in my improved construction, and this may be operated from any suitable source of power; but as specifically shown I employ a pneumatic motor operated by the suction or vacuum derived from the inlet manifold of the engine.

In the drawings:

Figure 1 is a side elevation of an internal combustion engine and cooling system to which my improvement is applied;

Figure 2 is a front elevation thereof, partly in section;

Figure 3 is a section through the pneumatic motor; and

Figure 4 is a section through the thermal motor.

A is an internal combustion engine provided with an inlet manifold B connected to the carburetor C. D is a radiator which is connected to the water-jacket of the engine by the out-going and return conduits E and F. G is a series of shutters arranged to cover a portion or all of the radiating surface and to vary the quantity of air which is accessible to the radiator. As shown, these shutters are formed by stationary and movable register slides H and H', the former being attached to the radiator frame and the latter guided to be movable in relation thereto.

To actuate the movable register slide H', a pneumatic motor is provided, preferably

comprising a cylinder I having a piston J therein, which is connected by a shank K to said movable slide. The cylinder I is secured in fixed position and has connected thereto a conduit L which leads to the inlet manifold B of the engine. At one point in this conduit there is arranged a valve M which is controlled by a thermal motor under the influence of the heat from the engine. Preferably, the thermal motor is secured to the outlet conduit E of the water cooling system and comprises a bar N inserted into the conduit E so as to transfer heat from said conduit to the thermostat member which carries the valve M.

With the construction described in operation, the movable shutter is held normally in one position, either opened or closed, by a suitable yielding pressure, such as that of a spring O in the cylinder I bearing against the piston J. When the engine is operating the suction produced in the intake manifold will be communicated to the conduit L and through the latter to the cylinder I, if the valve M is opened. The fall in pressure in the cylinder will cause the atmospheric pressure operating on the outer end of the piston to overcome the pressure of the spring and to shift the slide. Whenever the temperature of the water passing through the conduit E changes, this will cause a corresponding heating of the bar N and an expansion of the thermostatic member carrying the valve M, which at a predetermined temperature will close the valve M, cutting off connection between the cylinder I and the suction conduit and permitting the spring O to return the piston J. Assuming that the valve M is open at the low temperature limit and is closed at the high temperature limit, the motor must be so arranged that the spring will open the shutters and the suction will close the same. Thus when the engine is cold, but in operation, the suction will be communicated to the cylinder I and the piston operated to close the shutters, facilitating the heating of the motor and circulating water until the desired temperature is obtained. Any further rise in temperature will cause the warping of the bar N and the gradual closing of the valve M, which will result in gradually opening the shutters, to permit more air to pass through the radiator and to effect gradual cooling.

It is obvious that in the construction described, a much more sensitive and more ac-

curate operating device is obtained than where the work of shifting the shutters must be performed by a thermal motor operating under slight temperature changes.

5. What I claim as my invention is:—

1. The combination of an internal combustion engine, a cooling system therefor including a radiator, means for controlling the flow of air through the radiator, said means comprising a shutter device associated with the radiator, means directly responsive to suction produced in the engine cylinders for holding said shutter device closed until the engine reaches a predetermined temperature, 10 and a thermostatic device for rendering inoperative, the means responsive to suction when the engine reaches a predetermined temperature.

2. The combination of an internal combustion engine, a cooling system therefor including a radiator, means for controlling the flow of air through the radiator, said means comprising a shutter device associated with the 20

radiator, means directly responsive to suction produced in the engine cylinders for 25 holding said shutter device closed until the engine reaches a predetermined temperature, and means for moving such shutters to open position, automatically, upon the suction being shut off. 30

3. The combination of an internal combustion engine, a cooling system therefor including a radiator, means for controlling the flow of air through the radiator, said means comprising a shutter device associated with the 35 radiator, and means automatically operating incident to the operation of the engine for holding said shutter device closed until the engine reaches a predetermined temperature, and a thermostatic device for rendering said 40 last-mentioned means inoperative when the engine reaches a predetermined temperature.

In testimony whereof I affix my signature.

FREDERICK M. FURBER.
